UNITED STATES PATENT OFFICE.

FREDERICK L. H. SIMS, OF SOUTHAMPTON, ONTARIO, CANADA.

FOLDING BED.

Application filed July 24, 1922. Serial No. 577,262.

To all whom it may concern:

Be it known that I, FREDERICK L. H. SIMS, of the town of Southampton, in the county of Bruce, Province of Ontario, Canada, have invented certain new and useful Improvements in Folding Beds, of which the following is a specification.

This invention relates to folding beds adapted, when folded, to be contained in a sofa like housing such for example as the housing shown and described in my co-pending application No. 577,261 dated July 24th 1922, and my object is to devise a strong and easily folded bed which when extended for use carries the mattress at a satisfactory height from the floor and in which the frame work is automatically reduced in height when the bed is folded to enable it to be contained in a housing provided with a seat of ample depth having its upper surface at a normal height from the floor. It is also my object to so design the mechanism that, when extended, it is automatically locked against accidentally folding up and so that it may, when folded, be stowed away in an up ended position.

I attain my objects by means of the constructions hereinafter described and illustrated in the accompanying drawings in which—

Fig. 1 is a side elevation of a folding bed constructed in accordance with my invention and in extended position;

Fig. 2 a plan view of part of the same;

Fig. 3 a side elevation showing the bed folded, parts of the truck being in section;

Fig. 4 a plan view, partly in section, showing the parts in the position shown in Fig. 3; and

Fig. 5 a front elevation of the truck, partly broken away and partly in section.

Fig. 6 is a detail view of a portion of a bent lever and its connections.

In the drawings like numerals of reference indicate corresponding parts in the different figures.

Briefly the device comprises a truck supporting a mattress frame formed in three sections hinged together with rule joints, the pivots of one pair of joints extending into bearings at the sides of the front of the truck, on the axes of which the mattress frame, when extended, may teeter. When so extended the mattress frame is supported by two pairs of legs pivoted on the truck

frame, and a third pair pivoted at the outer end of an end section of the mattress frame and adapted to engage the floor. Means are provided for swinging the legs to and from their mattress frame supporting position. When the mattress frame is folded the inner and outer sections occupy substantially horizontal positions one above the other and the intermediate section a substantially vertical position at one end of the truck. Means are also provided whereby the axis on which the mattress frame teeters is automatically raised when the mattress frame is extended to raise the latter to a suitable bed height, and lowered when the mattress frame is folded to reduce the height to facilitate stowage as hereinbefore referred to.

1 is the truck constructed and braced in any suitable manner and preferably formed of angle bars. At its rear end the truck is provided with suitably supported ground wheels 2. The other end of the truck is supported by a pair of bent levers 3 pivoted on the truck, their lower ends forming feet provided with ground wheels 4. It is evident that by rocking the levers 3 the adjacent end of the truck may be raised and lowered. The method of supporting, constructing and operating these levers to so actuate the truck is hereinafter more fully described.

On the truck is mounted a mattress frame formed in three sections 5, 6 and 7. The inner section 5 and the outer section 7 are formed of T-angle bars. The intermediate section 6 is formed at its middle of L-section and near its ends of T-section. This mattress frame is in the main constructed as specifically set forth in my co-pending application No. 520986, though the means for supporting it are varied.

Adjacent the pivots 8 and 9, the intermediate section is formed with shoulders 10 adapted to engage the stems of the T-section angles of the adjacent mattress frame sections to limit the hinging of the parts on one another through an angle of about 90°.

The mattress frame is pivotally connected with the truck, preferably in alignment with and by the pivots 9, which are cast on the intermediate section. These pivots 9, it will be noted, are substantially in the same vertical plane as the points of contact of the wheels 4 with the ground,

when the mattress frame is folded. (See Fig. 3). When the mattress frame is extended as shown in Fig. 1, the free end of the inner section 5 is supported by means of the legs 11 which are pivoted intermediate of their ends on the truck, and have their upper ends notched to form a hook to engage projections 12 on the sides of the mattress frame to support it.

10 The mattress frame adjacent the pivots 8 is supported when in the position shown in Fig. 1 by means of the legs 13 pivotally connected at their lower ends with the truck and adapted to engage the projections 29 on the mattress frame. The outer end of the outer section 7 of the mattress frame is supported by means of the legs 14 pivoted on the sides of the mattress section. It is desirable that when the bed is to be folded that the legs should be simultaneously brought to an inoperative position, and I arrange to effect this through the operation of a movable head board, which is arranged also to serve as a mattress retaining device.

15 The head board 15 is connected to a pair of bent arms 16 pivoted on the sides of the mattress frame and preferably inside the flanges thereof to economize in the width of the structure. These arms are pivotally connected to connecting bars 17 pivotally connected at 19 with bent levers 18 pivotally connected at their lower ends inside the sides of the front of the truck to economize space in width. If connected outside these 20 levers could be straight but, being inside and as the pivot points 19 require, when the device is folded, to come into alignment with the pivots 9 they require to be bent to avoid interference with other parts. When

25 the mattress frame is extended, the pivot points 19 lie between the pivots 9 and the head board as shown. As long therefore as the movable head board is retained in its upright position, the outer end of the section 7 of the mattress frame cannot be raised. The connecting bars 17 are connected with the legs 14 by pivoted links 20. The upper ends of the legs extend above their pivots and a latch 21 is provided for 30 each leg pivoted on the mattress frame and formed with jaws 22 adapted to engage over the upper end of the adjacent leg as shown particularly in Fig. 1. A bail 23 connects these latches 21 so that they may be simultaneously lifted to free the legs. This then permits the legs to swing inwardly and upwardly as the head board is swung to the position shown in dotted lines in Fig. 1.

35 The connecting bars, it will also be seen, swing rearwardly the levers 18 and the levers and connecting bars are so proportioned that the pivotal points 19 between the levers and the connecting bars are brought into alignment with the pivots 9, and when in this position and the device is

folded the connecting bars to hold the head board as a mattress gripping device as hereinafter referred to. The outer section of the mattress frame is now free to swing up.

70 At the time the bent levers 18 have reached the position just described, their lower ends 25 have come into engagement with the side members of the adjacent end of the truck frame so that the levers can swing no further.

75 Pivoted connected with the levers 18 are the connecting rods 27, the other ends of these connecting rods being pivotally connected with the lower ends of the legs 11. Links 28 are pivotally connected with the connecting rod 27 and the legs 13. From this it follows that the movement of the head board hereinbefore referred to not only draws up the legs 14, but also swings 80 the legs 11 from engagement with the projections 12 and the legs 13 from engagement below the projections 29 secured to the sides of the intermediate mattress frame section 6.

85 When the legs are brought to their inoperative position by the bringing of the movable head board to its mattress engaging position, the outer section 7 is free to be raised at its outer end, the whole mattress frame then teetering on its pivotal connections with the truck. As the outer mattress frame section is raised, the section 5 is lowered, while the projections 12 thereon finally come into engagement with the diagonal braces 31 which brace the side members 47 of the adjacent end of the frame and also form tracks down which the projections may ride until the sides of the section rest upon the cross bar 32 of the truck as shown in Fig. 3. The diagonal braces 100 31 also serve the useful purpose of keeping the mattress fabric clear of the cross member 32 of the truck frame, and also at all times clear of the floor.

105 As the outer section of the mattress frame is swung towards its final position shown in Fig. 3, the shoulders of its joints with the intermediate section are engaged so that it will rock the sides of the intermediate section to the vertical position, the outer part 110 of the mattress frame then lying substantially horizontal and parallel to the section 5 which lies below it.

115 The free ends of the sections 5 and 7 are held spaced by means of the fixed end 120 boards 33, which are secured by means of arms 34 to the ends of their respective sections.

125 It will be noted that the movable head board has retained its mattress engaging position during the operation and holds its end of the mattress firmly against the mattress fabric supported by the outer mattress frame section 7, so that the mattress carried by the device folds properly as the 130

bed is closed. This action of the movable head board is due to the fact that, as hereinbefore described, the bent levers 18 are restrained from any movement which would 5 tend to release the head board from its engagement by the engagement of the ends 25 of the levers 18 with the sides of the adjacent end of the truck frame, at all times after the section of the mattress frame carrying the movable head board, when the device is being folded, attains a position perpendicularly above or beyond the axis of the pivots 9 since after that position is attained any movement of the head board to 10 release its grip tends to farther rock the bent levers 18 which is resisted by their engagement with the frame as stated above.

As hereinbefore stated, the bent levers 3 are operable to raise and lower the end of 20 the truck frame supporting the pivotal connections between the sectional mattress frame and truck. The movement of these bent levers is effected by connections between their upper ends and the outer mattress frame section. The connection at each side 25 comprises a jointed link 35 pivotally connected with the outer end of the adjacent lever and the side of the mattress frame section a suitable distance from the pivots 9.

30 The links are so positioned that the lines joining their points of connection with the levers and the mattress frame section lie below the pivots 9, so that when the bed is extended as shown in Fig. 1, the weight supported thereon has no tendency to lift the outer section of the mattress frame. When, 35 however, the mattress frame section is swung up the levers may swing until they occupy the position shown in Fig. 3, in which projections 42 secured on the lower part of the levers 3 engage the under sides of the side members of the truck frame. By this operation the height of the pivots 9 above the 40 floor level has been considerably reduced so that the truck with the mattress frame folded thereon as shown in Fig. 3 will fit into a housing of which the top is materially lower than would otherwise be necessary if the 45 height of the device were not so reduced, while when the device is extended the mattress is supported at a height greater than is usual in folding beds. The links are jointed, as shown, since the movement of the 50 mattress frame section 7 is through an arc of about 180°, while the bent levers 3 have merely to swing through an arc of approximately 30°. The links may thus hinge on 55 one another as shown in Fig. 3.

60 When the links are extended, a projection 36 on one part is adapted to engage a shoulder 37 formed on the other part, thus making them, when extended, substantially rigid as regards forces operating to break the joint upwardly.

65 It is necessary to provide a transverse

brace, to take the strain of the springs employed with the mattress fabric supported by the mattress frame, at or about the point of connection between the intermediate and inner sections of the mattress frame. For 70 this purpose I provide the bail-shaped brace 38, preferably formed of T-angle bars. The ends of this brace are pivotally connected at 75 39 to the sides of the mattress frame section 5 adjacent the pivots 8 and in such position that shoulders 40 formed on the ends will engage beneath the stems of the T-section bars to maintain the brace in the position shown in Fig. 1 when the mattress frame is extended for use. The position is such 80 that when the section 5 of the mattress frame is tilted due to the operation of folding the bed that the brace will not swing to or past a vertical position, so that it is readily folded up to the position shown in Fig. 3. 85

To swing the brace upwardly as described it is provided with cranked arms 41 which, during the process of folding the mattress frame, are adapted to engage the inwardly extending legs of the angle bar side bottom 90 members of the truck frame. The brace is thus held up as the sections of the mattress frame are folded until the brace finally assumes the position shown in Fig. 3. With this arrangement no spring is required to 95 raise the brace.

While the general arrangement of the truck frame will be understood from the description hereinbefore given, yet the special construction of the forward end of the truck 100 frame is of considerable importance, as this must be designed to give great strength and rigidity. It is also important that the end of the frame should be so constructed that it will not catch on any of the parts of the mattress fabric when the mattress frame is folded.

105 The side members 47 are formed of two angle bar members secured together to form a channel member, as shown particularly 110 in Fig. 2 of the drawings. One of these may be of lighter material than the other. These are cut away at the top and slightly bent inwardly to form lugs 45, in which are formed the bearings for the pivots 9, which form the axis on which the extended mattress frame may rock.

115 The cross bar 30 has its ends extended through semi-circular openings cut through the sides of the inner angle bars of the 120 sides 44, the ends of the bar being suitably secured to the bottom of the channel formed by the two angle bar members. The diagonal braces 26 are each secured to the cross bar 30, and also extended through 125 openings cut through the sides of the inner angle bar member of the sides 44 and are similarly secured to the bottoms of the channels. The inner side of the cross bar 30 is rounded to prevent interference with the 130

fabric of the mattress frame as hereinbefore referred to.

It will be noted on reference to Fig. 1 that the pivot of each leg 14 on the outer mattress frame section is set closer to the forward side of the leg than the rear side. This facilitates the folding of the leg close up under the mattress frame and saves about $\frac{3}{8}$ of an inch in the total height of the device when folded, which is an advantage when the device is to be stowed in restricted space. To avoid the tendency of the leg to tilt inwardly the pivot of the link on the leg and the pivot of the roller 46 by means of which the leg contacts with the floor are set on a line diagonal to the back and front edges of the leg, so that though the leg inclines slightly outwardly the weight acts perpendicularly to the point of support.

Particular attention should be called to the shape of and arrangement of the legs 11, which differ in shape from the legs 13 and swing oppositely. The legs 11 are supported on the side members 47 of the adjacent end 25 of the truck frame at a higher level than the pivotal supports of the legs 13. As these legs 11 must lie within the boundaries of the folded mattress frame as shown in Fig. 3, they are necessarily pivoted intermediate their ends so as to swing inwardly and the connecting rods 27 which are pivotally connected to the lower ends. The legs 11 are bent so that they will not, when the mattress frame is folded, interfere with the fixed head board 33 or the projections 12.

As it is important that the parts of the mattress frame, when it has been extended, should come accurately to the positions of engagement with the legs 11 and 13, it is preferably to provide means of adjustment in the rule joints connecting the sections. For this purpose the engagement of each joint between the side members and the intermediate section of the mattress frame 40 and the stems of the T-section side members of the inner and outer sections of the mattress frame should be by means of set screws 49 threaded through the ends of the side of the intermediate section and engaging the stems of the side members, as shown.

While the general arrangement of the levers 3 will be understood from the description previously given, the details of construction of these levers are of considerable importance. To get the desirable amount of lift, the lower arms of these bent levers must be over 6 inches in length between the journal of the roller 4 and the pivots of the bent levers on the lower ends of the diagonal side braces 48 of the side of the truck frame. It becomes necessary therefore to carefully design the parts to resist any normal side strain while keeping the cost down as much as possible. This is accomplished by providing the lower part of each bent lever with

a strap 43 riveted thereto and offset at each end. The lower end of the side brace 48 is embraced between the leg and strap, and also the roller 4 at the lower end of the leg.

The operation of the device is as follows, assuming the parts to be in the position shown in Fig. 1. The first operation is to pull up on the bail 23 to release the latches 21 from engagement with the upper ends of the legs 14, and to then push the movable head board and mattress retainer to the position shown in dotted lines in this figure. This operation moves the legs 11, 13 and 14 to their respective inoperative positions. The instant the legs are disengaged, the outer end of the outer section 7 of the mattress frame may be elevated. This operation rocks the levers 3 and lowers the adjacent end of the truck frame. The sections of the mattress frame tilt on the pivots 9 until the projections 12 strike the diagonal braces 31, down which they ride and the further folding of the mattress frame is an hereinbefore described. By a reversal of the movements, the mattress frame is extended. When all the parts are extended and the movable head board raised, the latches 21 are re-engaged with the upper end of the legs 14 as hereinbefore described.

It will be noted that as the mattress frame is extended the pivots 9 move to a position between the vertical planes in which lie the points of contact of the wheels 2 and 4 with the ground. This tends to overcome a tendency to tip the truck on the wheels 4 as the mattress frame is unfolded.

The supporting of the mattress frame section 5 on the diagonal braces also materially aids in this result and the projections 12 are preferably positioned to take as much of the weight of the section 5 off the pivots as possible.

It should be also noted that the various links, levers and connecting parts are bent or offset as may be necessary to enable them to clear one another as they are moved to effect the various operations.

What I claim as my invention is:

1. In a folding bed, the combination of a truck adapted adjacent one end to rest on the floor; a pair of levers pivoted on the truck and extending towards the other end of the truck to form feet and rockable to tilt the truck on the end resting on the floor; a mattress frame formed in sections hinged together and pivotally supported on said truck adjacent the end supported by the movable feet; and means connected with the mattress frame for rocking said foot levers to tilt the truck, the pivots of the mattress frame on the truck being positioned so that they are substantially in the same vertical plane as the points of contact of the movable feet with the floor, when the truck is in its lowered position, whereby they shift to

- a position between said plane and the vertical plane in which lie the points of contact of the other end of the truck with the floor, when the truck is in up-tilted position. 70
- 5 2. In a folding bed the combination of a truck; a mattress frame formed in sections hinged together and pivotally supported intermediate of its ends on said truck; means for raising and lowering the part of the truck on which the mattress frame is pivoted; means whereby the folding of the mattress frame actuates the truck raising and lowering means to lower the aforesaid part of the truck and the extension of the mattress frame actuates the said means to raise the said part of the truck; means carried by the truck for releasably supporting the part or parts of the mattress frame at one side of the pivotal support; and folding legs 75 adapted to support from the floor the other part or parts of the mattress frame. 80
- 10 3. In a folding bed the combination of a truck adapted adjacent one end to rest on the floor; feet adjacent the other end of the truck connected therewith and adjustable up and down relative thereto to tilt the truck on the end resting on the floor; a mattress frame formed in sections hinged together and pivotally supported on said truck adjacent the end supported by the movable feet; and means connected with the mattress frame for extending and retracting said feet relative to the truck as the mattress frame is extended or folded. 85
- 15 4. In a folding bed the combination of a truck adapted adjacent one end to rest on the floor; a pair of bent levers pivoted on the truck, their lower ends forming feet adjacent the other end of the truck; said levers when actuated being adapted to tilt the truck on the end resting on the floor; a folding sectional mattress frame pivoted on the truck adjacent the said other end; and links pivotally connected with said frame and the upper ends of the bent levers. 90
- 20 5. In a folding bed the combination of a truck; a mattress frame formed in three sections hinged together, and pivotally supported intermediate of its ends on said truck; two pairs of legs pivotally connected to the truck and adapted to support the inner and intermediate sections of the mattress frame; a pair of legs pivoted on the outer section of the mattress frame; a hinged head board carried on the outer section; and means whereby the swinging of the head board up and down will move all the legs to and from their mattress-frame supporting position. 95
- 25 6. In a folding bed the combination of a truck; a mattress frame formed in three sections hinged together, and pivotally supported intermediate of its ends on said truck; two pairs of legs pivotally connected to the truck and adapted to support the inner and intermediate sections of the mattress frame; a pair of legs pivoted on the outer section of the mattress frame; and means for simultaneously moving all the legs to and from their operative positions. 100
- 30 7. In a folding bed the combination of a truck; a mattress frame formed in three sections hinged together, and pivotally supported intermediate of its ends on said truck; two pairs of legs pivotally connected to the truck and adapted to support the inner and intermediate sections of the mattress frame; a pair of legs pivoted on the outer section of the mattress frame; and means for simultaneously moving all the legs to and from their operative positions; and a latch for locking one pair of legs, and therefore the others, in their operative position. 105
- 35 8. In a folding bed the combination of a truck; a mattress frame formed in three sections hinged together, and pivotally supported intermediate of its ends on said truck; two pairs of legs pivotally connected to the truck and adapted to support the inner and intermediate sections of the mattress frame; a pair of legs pivoted on the outer section of the mattress frame; a hinged head board carried on the outer section; and means whereby the swinging of the head board up and down will move all the pairs of legs to and from their mattress-frame supporting position; and means for locking the last mentioned pair of legs and therefore the others, in their operative position. 110
- 40 9. In a folding bed the combination of a truck; a mattress frame formed in three sections hinged together and pivotally supported intermediate of its ends on said truck; two pairs of legs pivotally connected to the truck and adapted to support the inner and intermediate sections of the mattress frame; a pair of legs pivoted on the outer section of the mattress frame; a hinged head board carried on the outer section; means whereby the swinging of the head board up and down will move all the pairs of legs to and from their mattress-frame supporting position; and means for locking the last mentioned pair of legs and therefore the others, in their operative position. 115
- 45 10. In a folding bed the combination of a truck, a mattress frame formed in three sections hinged together and pivotally connected, intermediate of its ends, on said truck; means for raising and lowering the part of the truck on which the mattress frame is pivoted; two pairs of legs pivotally connected to the truck and adapted to support the inner and intermediate sections of the mattress frame; a pair of legs pivoted on the outer section of the mattress frame; means for simultaneously moving all the legs to and from their operative positions; and means connected with the outer section of the mattress frame and op- 120
- 50 65 125
- 55 60 65 130

erable by the swinging of said section to actuate the raising and lowering means for the truck.

11. In a folding bed the combination of a truck; a mattress frame section pivoted on said truck; a pair of arms pivoted on said mattress frame section; a head board carried by said arms and adapted to be brought by the swinging of said arms to and from a mattress engaging position; levers pivoted on the truck below the points of connection of the mattress frame; connecting bars pivotally connected with the aforesaid arms and the levers, the parts being so proportioned that the pivotal connections between said bars and the levers lie between the pivot points of the mattress frame on the truck and the head board when the latter is raised and are brought into alinement with the said pivots when the board is in its mattress engaging position; and means preventing the levers swinging past the said position of pivotal alinement.

12. In a folding bed the combination of a truck; a mattress frame section pivoted on said truck; a pair of arms pivoted on said mattress frame section; a head board carried by said arms adapted to be brought by the swinging of said arms to and from a mattress engaging position; levers pivoted on the truck below the points of connection of the mattress frame; connecting bars pivotally connected with the aforesaid arms and the levers, the parts being so proportioned that the pivotal connections between said bars and the levers lie between the pivot points of the mattress frame on the truck and the head board when the latter is raised and are brought into alinement with the said pivots when the board is in its mattress engaging position; and means for preventing the levers swinging past the said position of pivotal alinement; legs pivoted on said mattress frame section adjacent the head board; and pivoted links connecting said legs with adjacent parts moving with the head board aforesaid.

13. In a folding bed the combination of a truck; a mattress frame section pivoted on said truck; a pair of arms pivoted on said mattress frame section; a head board carried by said arms adapted to be brought by the swinging of said arms to and from a mattress engaging position; levers pivoted on the truck below the points of connection of the mattress frame; connecting bars pivotally connected with the aforesaid arms and the levers, the parts being so proportioned that the pivotal connections between said bars and the levers lie between the pivot points of the mattress frame on the truck and the head board when the latter is raised and are brought into alinement with the said pivots when the board is in its mattress engaging position; means preventing

the levers swinging past the said position of pivotal alinement; legs pivoted on said mattress frame section adjacent the head board; pivoted links connecting said legs with the connecting bars aforesaid; and means for releasably locking said legs in their mattress frame supporting position.

14. In a folding bed the combination of a truck adapted adjacent one end to rest on the floor; a pair of bent levers pivoted on the truck, their lower ends forming feet adjacent the other end of the truck; a folding sectional mattress frame pivoted on the truck adjacent the latter end; and folding links pivotally connected with said frame and the upper ends of the bent levers.

15. In a folding bed the combination of a truck formed with lower side members; a mattress frame formed in three sections hinged together and pivotally supported on said truck; a bent brace pivotally connected with the sides of the mattress frame; and cranked arms on said brace adapted to engage the lower side members of the truck to fold up the brace when the mattress frame is folded.

16. In a folding bed the combination of a truck formed with lower side members; a mattress frame formed in three sections hinged together and pivotally supported on said truck; a bent brace pivotally connected with the sides of the mattress frame; cranked arms on said brace adapted to engage the lower side members of the truck to fold up the brace when the mattress frame is folded; and means preventing the brace swinging to a vertical position when the mattress frame is extended or in intermediate positions.

17. In a folding bed the combination of a truck; a mattress frame section pivoted on said truck; a pair of arms pivoted on said mattress frame section; a head board carried by said arms adapted to be brought by the swinging of said arms to and from a mattress engaging position; levers pivoted on the truck below the points of connection of the mattress frame; and connecting bars pivotally connected with the aforesaid arms and the levers, the parts being so proportioned that the pivotal connections between said bars and the levers lie between the pivot points of the mattress frame on the truck and the head board when the latter is raised and are brought into alinement with the said pivots when the board is in its mattress engaging position.

18. In a folding bed, the combination of a truck adapted adjacent one end to rest on the floor; a pair of levers pivoted on the truck and extending towards the other end of the truck to form feet and rockable to tilt the truck on the end resting on the floor; a mattress frame formed of inner, outer and intermediate sections hinged to

gether and pivotally supported on said truck so that the intermediate section may swing to a position depending from said pivots with the inner adjacent section lying at an angle thereto; guides inclined downwardly and inwardly; projections on said mattress frame section adapted to ride on said guides downwardly as the mattress frame is folded and upwardly as it is extended; and means connected with the mattress frame for rocking said foot levers to tilt the truck, the pivots of the mattress frame on the truck being positioned so that they are substantially in the same vertical plane as the points of contact of the feet with the floor, when the truck is in its lowered position, whereby they shift to a position between said plane and the vertical plane in which lie the points of contact of the other end of the truck with the floor, when the truck is in its uptilted position.

19. In a folding bed the combination of a truck; a mattress frame formed in sections hinged together and pivotally supported on said truck so that one section may swing to and from a position depending from said pivot with an outer section lying at an angle thereto or both sections may lie substantially horizontal; a pair of supporting legs for said sections pivoted at their lower ends on the truck frame; a pair of supporting legs for said sections pivoted intermediate their ends on the truck frame; and connections for simultaneously swinging said legs to and from their mattress frame supporting position connected with one pair of said legs above their pivots and the other pair below their pivots.

20. In a folding bed the combination of a truck; a mattress frame formed in sections hinged together and pivotally supported on said truck so that one section may swing to and from a position depending from said pivot with an outer section lying at an angle thereto or both sections may lie substantially horizontal; a pair of supporting legs for said sections pivoted on the truck frame adjacent the free end of the outer section of the mattress frame and provided at their upper ends with notches; projections on said mattress frame adapted to engage in these notches to resist either up-

ward or downward movement of the outer mattress frame section; and a second pair of legs pivoted on the mattress frame adapted to support the same adjacent the junction between the two sections.

21. In a folding bed, the combination of a truck; a mattress frame formed in three sections hinged together and pivotally supported intermediate of its ends adjacent one end of said truck, said sections, when the bed is folded, assuming a position with the intermediate section depending from said pivotal connections and the other sections substantially horizontal one above the other; means for raising and lowering the end of the truck on which the mattress frame is pivoted; and operating means whereby the raising and lowering of the upper or outer section of the mattress frame actuates the aforesaid means to raise and lower the aforesaid end of the truck, said operating means including a lost motion device whereby the raising of the truck is deferred until the mattress frame is partly unfolded.

22. In a foldable mattress frame formed in sections pivotally connected together; shoulders formed on one section adjacent each pivot; and a set screw threaded through the other part adjacent each pivot adapted to engage the shoulder to limit the unfolding movement of the adjacent section.

23. In a folding bed, the combination of a truck; a mattress frame formed in sections hinged together and pivotally supported on said truck adjacent one end so that one section may swing to a position depending from the pivots with an inner section lying at an angle thereto; upright side members forming part of the truck frame at the end remote from the pivots; legs pivoted at the upper ends of said uprights; projections on the inner mattress frame section engageable by said legs when said inner section is raised to a substantially horizontal position at the level of the pivots; and diagonal side braces for the truck frame extending downwardly and inwardly from said uprights, said projections being adapted to ride over said braces.

Signed at Toronto, Canada, this 12th day of July, 1922.

FREDERICK L. H. SIMS.
